(57) **CLAIM**

The ornamental design for a battery pack as shown and described.

DESCRIPTION

FIG. 1 is a perspective view of a battery pack showing the new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom view thereof;

FIG. 8 is an enlarged view thereof, taken from the portion labeled 'FIG. 8' in FIG. 4;

FIG. 9 is an enlarged view thereof, taken from the portion labeled 'FIG. 9' in FIG. 4;

FIG. 10 is an enlarged view thereof, taken from the portion labeled 'FIG. 10' in FIG. 6;

FIG. 11 is an enlarged view thereof, taken from the portion labeled 'FIG. 11' in FIG. 6;

FIG. 12 is an enlarged view thereof, taken from the portion labeled 'FIG. 12' in FIG. 7; and,

FIG. 13 is an enlarged view thereof, taken from the portion labeled 'FIG. 13' in FIG. 7.

The dash-dash broken lines in the drawings depict portions of the battery pack that form no part of the claimed design. The dot-dash broken lines represent annotations of the enlarged views and form no part of the claimed design.

1 Claim, 13 Drawing Sheets
